UNITED STATES PATENT OFFICE.

CHARLES L. HEISLER, OF DUNKIRK, NEW YORK, ASSIGNOR OF ONE-HALF TO
EDWARD NICHOLS, OF SAME PLACE.

CORN-SHELLER.

SPECIFICATION forming part of Letters Patent No. 405,838, dated June 25, 1889.

Application filed January 21, 1889. Serial No. 297,027. (No model.)

To all whom it may concern:

Be it known that I, CHARLES L. HEISLER, a citizen of the United States, residing at Dunkirk, in the county of Chautauqua and State of New York, have made certain new and useful 5 Improvements in Corn-Shellers, of which the following is a specification.

My invention relates to an adjusting device to be applied to a corn-sheller, by means of 10 which the distance between the shelling-faces may be changed in order to accommodate the machine to the size of the ears of corn being operated upon.

In the drawing, which is a central vertical 15 section of a machine embodying my invention, parts being in elevation, P represents the frame-work, in which is supported a screening device or receiver A of any usual construction, and the shelling devices, which latter are arranged to deliver into the receiver A. These 20 shelling devices are shown as consisting of an internally studded and ribbed hopper or shell B, contracted toward the center, and a studded revolving cone C, mounted centrally 25 within the shell.

The parts thus far described are of usual construction.

The cone C is mounted upon a shaft made in two sections D and E, the lower section D, 30 serving as the driver for the cone, being belted to any desired motor. The cone is splined upon the lower section D of the shaft, so that it may be moved longitudinally thereon in order to bring the studded surfaces of the 35 cone and shell nearer to or farther from each other as the size of the ears of corn being shelled may require. The cone C is supported or suspended from above by the upper section E of the shaft, the lower end of which 40 section enters a socket or aperture in the upper end or apex of the cone, and in which it is clamped by the bolt b. The wall of the cone surrounding the aperture or socket into which the end of the section E of the shaft extends 45 is split or cut from its upper edge downward, so that the parts of the wall thus separated may be drawn toward each other by the bolt b, and thus be made to tightly clamp the shaft, which would not be possible were the said 50 wall integral and rigid. The section E of the

shaft turns freely in an adjustable sleeve-bearing F, which is preferably threaded to engage with a screw-threaded socket or nut I in a yoke K, the shaft being provided at its upper end with a head e, which bears upon 55 the upper face of the bearing F, or, preferably, upon a ring or collar L of Babbitt or similar metal, and thereby sustains the weight of the cone. By raising and lowering the bearing by means of the screw or otherwise 60 the shaft-section E is caused to rise and fall, and thus change the distance between the shelling-surfaces, as will be understood without detailed description.

J is a set-screw adapted to bear upon the 65 bearing F and hold it in position after proper adjustment. The head of the bearing F is expanded into a cup-shaped receptacle f, adapted to receive a lubricant in the body of which the head e of the shaft-section E turns, 70 and more or less of which lubricant will work down the sides of the shaft, causing it to run freely in the sleeve of the bearing.

G represents a lid for closing the open end 75 of cup f.

The yoke K is preferably bolted to a flange k, projecting laterally from the upper end of the shell B, such flange being provided with a number of apertures m, which permit the yoke to be bolted to the shell in the most desirable position for feeding the corn into the machine. A feed hopper or chute may likewise be secured to such flange k, if found desirable.

Without limiting myself to the precise construction and arrangement of parts shown, I 85 claim—

1. The combination of the shell, the shaft in two sections, and the cone turning with and sliding on the lower section and adjustable vertically with the upper section, substantially as set forth.

2. The combination, with the shell and the cone, of the shaft in two sections, the upper section suspending the cone, and a stationary 95 adjustable bearing for the upper section of the shaft in which it turns, substantially as set forth.

3. The combination of the shell, the shaft in two sections, the cone turning with and slid- 100

ing on the lower section and adjustable with the upper section, the yoke K, and an adjusting-screw for the upper section of the shaft mounted in the said yoke, substantially as set forth.

4. The combination, with the cone and the shell, of the shaft in two sections, the upper section E being headed and supporting the cone, the stationary adjustable bearing provided with a sleeve in which the section E of the shaft turns, and above the upper face of which the head of the said section bears, substantially as set forth.

5. The combination of the driving-shaft, the

shelling-cone mounted thereon and provided with a socket or aperture at its upper end, the walls of which socket or aperture are cut, a shaft fitting into the said socket or aperture, and a clamping-bolt for securing the shaft in the socket or aperture, substantially as set forth.

In testimony whereof I have signed my name to this specification in the presence of two subscribing witnesses.

CHARLES L. HEISLER.
